METHOD OF PRESSING SEAMS FORMED
IN SHOE PARTS

Milton H. Roske, Malden, Mass., assignor to
United Shoe Machinery Corporation, Flemington, N. J., a corporation of New Jersey

Original application July 13, 1944, Serial No.
544,728. Divided and this application September 22, 1945, Serial No. 618,004

3 Claims. (Cl. 12—146)

1

This invention relates to methods of pressing seams formed in shoe parts, for example the back-seams of shoe uppers. These seams result from the stitching together of the marginal portions of the quarters of the shoe uppers. The stitching operation is performed with the outer surfaces of the margins of the upper material in face-to-face relation, and when the quarters are turned right side out the seam presents an undesirable inwardly extending ridge. It is customary in the manufacture of shoes to employ various devices to flatten this ridge.

It is an object of the present invention to provide an improved method of pressing seams of the character under consideration. In accordance with this object, the method, in one aspect, consists in feeding the work piece, tensioning it transversely of the seam, and pressing the seam while the work piece is being fed under tension. Such tensioning gives a better appearance to the finished work.

The method above referred to can conveniently be carried out upon the machine disclosed and claimed in my copending application Serial No. 544,728, filed July 13, 1944, of which the present application is a division. To facilitate an understanding of the improved method claimed in the present application, this machine will be described herein in connection with a drawing illustrating it.

Referring now to the accompanying drawing,

Fig. 1 is a left side view of the work engaging portions of the machine upon which the method can be carried out;

Fig. 2 is a front view of the members shown in Fig. 1; and

Fig. 3 is a large scale side elevation of the work engaging instrumentalities of the machine in operation upon a work piece.

The operating instrumentalities of the machine above referred to comprise a driven seam pressing or seam rubbing roll 10 of relatively large diameter, a work support 12, and a pair of driven feed rolls 14 and 16. The work is guided to the operating members by a seam crease guide 18 and a seam ridge guide 20.

The seam pressing roll 10 is a relatively narrow, disk-like member having a fluted periphery. It is secured upon a shaft 28 journaled in suitable bearings 29 carried by a pair of forwardly extending arms 30 rigidly secured to the frame of the machine, and is driven at high speed by any suitable means.

The feed roll 14 is mounted upon the lower end of an inclined shaft 42 which is journaled and

2

longitudinally slideable in a bearing 44. A compression spring 43 surrounding the shaft 42 and interposed between the upper face of the feed roll 14 and a washer 45 urges the shaft 42 down. 5 The washer 45 is held against upward movement by engagement with the lower end of a bushing 41 in the bearing 44.

The feed roll 16 is secured upon the lower end of an inclined shaft 78 journaled and longitudinally slideable in a bearing and is held down yielding to a stop position by a spring similar to the spring 43. The rolls 14 and 16 are similar to each other and are positioned on opposite sides of the pressing roll 10, the shafts 42 and 78 being downwardly inclined toward each other. The work engaging portions of the rolls 14 and 16 consist of rubber pads 88 set into cup-shaped ends of metal holders. The pads 88 have flat end faces which are presented to the work. These rolls are both driven at the same speed, which is materially less than the speed of the pressing roll 10. The direction of rotation of the various members is indicated by arrows on the drawings.

The work support comprises a resiliently supported roll 89 having a cylindrical periphery 90 (Fig. 3), which urges the work with yielding pressure against the rubbing roll 10. The axis of the roll 89 is positioned rearwardly (in the machine) of the common plane of the axes of the feed rolls 14 and 16. The opposite end faces of the roll 89 have conically beveled marginal portions 92 and 94. The roll 89 is carried by a shaft 96 which is journaled in a pair of spaced ears 98 mounted upon a plunger 100 guided for heightwise movement. A spring (not shown) acting upon the plunger 100 yieldingly urges the roll 89 upwardly to a position determined by a stop 128.

The seam crease guide 18 consists of an up-standing blade-like member curved about part 40 of the roll 89 and extending close to the locality of operation. The lower end of the crease guide 18 is carried by a bracket 112 which is secured to the ears 98.

The seam ridge guide 20 (Figs. 1 and 2) consists of an inverted channel or U-shaped member extending close to the locality of operation. The upper part of the guide 20 is straight and is guided for heightwise movement in a guideway 114 secured indirectly to the frame of the machine. The seam ridge guide 20 is yieldingly urged down to a stop position by tension spring 120 having its lower end secured to a pin 122 extending from the guide way 114. The upper end of the spring 120 is secured to a pin 124 on 50 the seam ridge guide 20. Downward movement

55

of the guide 20 is stopped by engagement of the upper end of a slot 160 in the guide 20 with a conical end of a screw 162 threaded into the wall of the guideway 114 and having a knurled head.

The method which constitutes the subject matter of the present application will now be described. The operator in carrying out this method presents to the machine a work piece W having a seam ridge R, holding the work piece in inside-out position, with the seam ridge entering the guide 20 and the seam crease lying over the guide 18. The feed rolls 14 and 16, under the yielding pressure of their springs 43, engage the leading edges of the work and press the work against the bevels 92 and 94, respectively. The feed rolls thus grip the work piece and advance it until the leading edge of the work piece is engaged by the pressing roll. The effect of the feed rolls thereafter is to control the feed of the work piece by holding it back against the tendency of the rapidly rotating pressing roll to eject it from the machine. The feed rolls 14 and 16 have another important function; they tension the work transversely of the seam. The axis of each of the feed rolls passes, not through the axis of the work support, but in advance of the axis of the work support (with respect to the direction of feed); and since, therefore, the axes of the feed rolls and the work support do not lie in a common plane, the feed rolls will not engage the work piece with the pure rolling contact, but will wipe or skid upon the surface of the work piece; the portion of each feed roll which grips the work will move in a direction having a component away from the seam as well as a component of feed control parallel to the seam. The components away from the seam will cause each roll to exert a wiping action upon the work piece in opposition to the other roll, and will thus result in a tensioning of the work piece between the two feed rolls. Such tensioning improves the appearance of the finished work.

Having described my invention, what I claim as new and desire to secure by Letters Patent of the United States is:

1. The method of pressing a seam formed by the joining of two pieces of sheet material in face-to-face relation adjacent to the edges of said pieces, which consists in feeding the material longitudinally of the seam, tensioning the material transversely of the seam, and pressing the seam while the material is being fed under tension.
2. The method of pressing a seam formed by the joining of two pieces of sheet material in face-to-face relation adjacent to the edges of said pieces, which consists in applying forces to the material on opposite sides of the seam, which forces are so directed as to have components in the direction of the seam to control the feed of the work and components transverse to the seam to tension the work, and pressing the seam while the material is being fed under such tension.
3. The method of pressing a seam formed by the joining of two pieces of sheet material in face-to-face relation adjacent to the edges of said pieces, which consists in feeding the work piece, wiping the portions of the work piece on opposite sides of the seam away from the seam to tension the work piece transversely of the seam, and pressing the seam while the material is being fed under tension.

MILTON H. ROSKE.
